To all whom it may concern:

Be it known that I, VERDRIE F. CLARK, a citizen
of the United States, residing at Jeffersonville, in
the county of Clark and State of Indiana, have
invented a new, original, and ornamental Design
for a Coal Burning Stoker, of which the following
is a specification, reference being had to the ac-
companying drawing, forming part thereof.

The figure is a perspective view of the stoker
showing my new design.

I claim:—

The ornamental design for a coal burning
stoker, as shown.

VERDRIE F. CLARK.
